CLAIM

The ornamental design for a battery for vacuum cleaner, as shown and described.

DESCRIPTION

FIG. 1 is a perspective view of a battery for vacuum cleaner, showing our new design;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof; and,

FIG. 8 is another perspective view thereof in an environment of use.

The broken lines shown in the drawings are included for the purpose of illustrating environmental structure and form no part of the claimed design.
